TYPEWRITING AND LIKE MACHINE

Henry A. Heinrich, Middletown, Conn., assignor
to Remington Rand Inc., Buffalo, N. Y., a cor-
poration of Delaware

Application August 25, 1937, Serial No. 160,863

3 Claims. (Cl. 197—82)

My invention relates to typewriting and like machines, and more particularly to improvements in the carriage escapement mechanism of such machines.

5 One of the main objects of my invention, generally stated, is to provide improved, highly efficient and reliable carriage feed mechanism.

Another object of my invention is to provide improved connecting means between the carriage and the escapement wheel in a machine of the type wherein the carriage in its entirety has a case shifting movement relative to the escapement wheel.

10 A further object of my invention more specifically stated is to provide a connecting means of the character specified that prevents the creation of back lash or lost motion between the carriage feed shaft or pinion and the escapement wheel, thereby overcoming the difficulties ordinarily presented due to such back lash.

20 To the above and other ends which will herein-after appear, my invention consists in the features of construction, arrangements of parts and combinations of devices set forth in the following description and particularly pointed out in the appended claims.

In the drawing, wherein like reference characters designate corresponding parts in the different views—

25 Fig. 1 is an enlarged, fragmentary, vertical sectional view of the carriage escapement mechanism and a portion of the case shifting mechanism of a No. 10 Remington Noiseless typewriting machine equipped with the devices of my invention.

30 Fig. 2 is an enlarged fragmentary horizontal sectional view taken on line 2—2 of Fig. 1 and viewed in the direction of the arrows at said line.

Fig. 3 is an enlarged detail plan view of a part 35 of the construction shown in Figs. 1 and 2.

40 My invention is in the nature of an improvement on the carriage feeding mechanism of the No. 10 Remington Noiseless typewriting machine or generally on the type of carriage feeding mechanism disclosed in Patent No. 1,219,213 to N. H. Anderson dated March 13, 1917.

45 The present invention, however, is likewise applicable to the No. 6 Remington Noiseless machine and to the No. 11 Remington machine.

50 I have shown my invention embodied, in the present instance, in a No. 10 Remington Noiseless machine in which the features of the present invention may be readily incorporated with but few changes in the existing structure. However, 55 it is to be understood that my invention is not

restricted to embodiment in such machines as those indicated above but may be employed in various other types of typewriting and like machines wherever found available.

I have shown in the accompanying drawing 5 only so much of the usual construction of the No. 10 Remington Noiseless machine as is necessary to arrive at a complete understanding of my invention in its embodiment therein.

In Fig. 1 a portion 5 of the usual cross member 10 of the machine frame is shown as supporting the case shifting rock shaft 6 by upstanding bearing lugs 7 in the usual manner. The usual case shiftable member or guide rail 8 has attached thereto depending brackets 9 which are pivoted 15 at 10 to spaced arms 11 carried by the rock shaft 6. The member 8 is guided by the usual means, not shown, for substantially vertical case shifting movement which is effected by rocking the shaft 6. 20

The shaft 6 is rocked for case shifting by the usual mechanism, only a portion of which is herein shown as including links 12 connected to an arm 13 adjustably mounted on a forward extension 14 of one of the rock shaft arms 11. A 25 toggle action is given the links 12 which rocks the shaft 6 in an anti-clockwise direction as viewed in Fig. 1 to raise the member 8 to upper case position shown in dotted lines in Fig. 1. The upper case position of the various shifted parts 30 is limited by an adjustable stop screw 16 carried by the arm 13 and engageable with the head 17 of a screw threaded into the cross member 5. The lower case position is limited by the usual stop mechanism which has not been shown. 35

The carriage of the present machine has not been shown in full but may be of the usual construction and includes the main support 20 provided with oppositely disposed grooved tracks or raceways 20^a. The carriage member 28 is mounted between oppositely disposed channels or tracks in the case shiftable member 8 by crossed anti-friction rollers 23 for longitudinal carriage feed movement in the usual manner. The carriage thus mounted is impelled in a letter space feed 40 direction by the usual spring drum, not shown. 45

The carriage movement in the letter space feed direction is controlled by the usual form of escapement devices including a releasable feed rack 25 pivotally mounted on the carriage member 20 to normally engage a feed pinion 26 fixedly secured at the upper end of a substantially vertically disposed feed shaft 27. This feed shaft is rotatively supported in place by a ball and socket bearing 28, pivoted at 28^a to a bracket 50 55

arm fixed to the case shiftable member 8 to be carried therewith in the case shifting movements of the latter.

Although for convenience, the parts in the present construction are shown in the drawing as disposed so that the feed shaft 27 for example appears vertical, it is to be understood that actually these parts are so mounted in the No. 10 Remington Noiseless and the No. 11 Remington machines that the feed shaft has approximately a ten degree fore and aft displacement from a vertical alignment. However, for the purposes of the present invention, it is merely necessary to understand that the case shifting movement of 15 the carriage is substantially parallel or in line with the axis of the feed shaft.

In the present instance, the carriage escapement mechanism including the escapement wheel and dog rocker assembly which controls the rotative movement of feed shaft 27 may be of the usual construction employed in No. 10 Remington Noiseless machines to afford letter spacing movements of the carriage under the force of the usual carriage spring drum. Thus, the escapement wheel designated as a whole by the reference numeral 30 is provided with an enlarged centrally disposed opening through which the lower end portion of the feed shaft 27 freely passes. A reduced diameter upper hub portion 31 of the escapement wheel is received in a bearing opening in an arm 32^a of an L-shaped bracket 32 which is rigidly attached at 33 to a cross member 34 of the machine frame. The escapement wheel 30 is mounted for rotation in the bearing opening in the bracket arm 32^a and is retained against downward vertical displacement by the usual tabulator brake drum 35 threaded upon a further reduced upper end portion 36 of the hub 31 and overlying the adjacent portion of the bracket arm 32^a. The shouldered portion 31^a of the hub 31 coacts with the under side of the bracket arm 32^a to prevent upward displacement of the escapement wheel.

The dog rocker assembly designated as a whole by the reference numeral 40 comprises, in the present instance, the usual dog rocker 41 (see Fig. 2) having down turned lateral end portions recessed to receive coned ends of pivot screws 42 carried by respective spaced arms 43 extending rearwardly and downwardly from the bracket 32. A forwardly extending arm 44 of the dog rocker 41 carries on the upper side thereof a holding dog 45 mounted thereon at 46 and biased to its normal position by a spring 47 to engage teeth 50 on the escapement wheel 30. The holding dog 45 is also mounted for a slight sliding movement against the force of a spring 48. A stepping dog 51 which is normally out of engagement with the teeth 50 is pivoted at 52 on the lower side of the arm 44 to receive a movement against the force of the same spring 47 that is also connected to the holding dog 45. The movement of the stepping dog 51 against the force of the spring 47 is limited by a stop arm 53 adjustably mounted at 54 in a rearward extending arm 55 of the dog rocker 41 and having its forward end entering a bifurcation (not shown) in the tail of stepping dog 51.

The dog rocker is biased to its normal position 70 by the usual spring 56 to engage a stop screw 57 with the edge of the associated bracket arm 43 and thereby limit the return movement of the dog rocker to normal position. The dog rocker 41 is rocked about the pivot screws 42 upon the actuation of any of the printing keys

or the space bar through the usual means which have not been shown.

While I have described in detail the escapement wheel, coacting feed dogs, dog rocker, etc., employed in the present instance, it should be 5 understood that so far as the present invention is concerned, any suitable devices may be employed in lieu of these parts.

It will now be clear that in an arrangement of the present type wherein the entire carriage receives a case shifting movement, the escapement wheel 30 must be connected to rotate with the feed shaft 27 and pinion 26 but, nevertheless, provision must be made to maintain the feed pinion at all times in cooperative relation with the 10 feed rack. This is attained in the present instance by affording longitudinal or axial case shifting movement of the feed shaft and feed pinion relative to the escapement wheel. In the construction ordinarily employed in said Remington Noiseless machines, the connection to attain these ends is provided for by oppositely disposed longitudinal ways or grooves in the feed shaft receiving anti-friction bearing balls carried in companion oppositely disposed grooves or ways 20 in the wall of a centrally located opening in the escapement wheel. A somewhat similar connection is also disclosed in the previously mentioned Patent No. 1,219,213.

In such constructions, it will be clear that the 30 point of connection between the feed shaft and the escapement wheel is very close to the center or axis of the feed shaft, and accordingly any looseness or clearance ordinarily encountered in manufacture of these connecting parts are created 35 by wear thereon in the use of the machine is multiplied several times at the teeth of the escapement wheel. In other words, the clearance or tolerance in the fit of the balls in the raceways or the wear which takes place at these points 40 might afford a very slight amount of relative rotative movement between the connected parts at the point near the axis of the feed shaft where the connection is made, but at a point spaced as far from the axis as the teeth of the escapement wheel, the relative rotative movement of the 45 connected parts is considerably multiplied.

It has been found in practice that when the point of connection between the parts is provided near the axis of the feed shaft as in said prior 50 constructions the extent of relative rotative movement is sufficient to at times cause considerable difficulty in the operation of the machine. This difficulty arises particularly during rapid operation of the machine when the back lash afforded 55 during the free movement of the escapement wheel allows it to get out of time with the oscillating up and down movement of the dog rocker. This may cause a piling of one printed character upon another as an escapement dog may move 60 up and down in the same interdental space of the escapement wheel instead of affording a complete letter space movement of the wheel. It has also been found that a certain amount of noise 65 in operating the machine is produced by this back lash between the escapement wheel and feed shaft.

It will further be clear that the wear resulting 70 from the case shifting motion is concentrated at the ball and groove connection close to the axis of the feed shaft and at two points only. This concentration of the wear together with the location of the wear near the axis causes the difficulties due to this back lash to materially increase as the machine is used.

It is the main purpose of my invention to provide a connecting means between the feed pinion, or feed shaft 27, and the escapement wheel 30 which will overcome these and other difficulties encountered by the prior connecting means. Generally stated, I overcome these difficulties with the aid of connecting means by which the feed shaft is connected to the escapement wheel at points which are spaced a sufficient distance from the axis of the feed shaft so that there can be little or no lost motion between the shaft and wheel and any such lost motion as may occur is not multiplied at the teeth of the escapement wheel and is not appreciable at such point. I also provide such a connecting means wherein the wear resulting from case shifting is distributed over an increased number of points, thereby reducing the extent of relative movement resulting from such wear.

The connecting means of my invention thus comprises in the present instance a plurality of connections between the feed shaft and the escapement wheel, which connections are spaced outwardly a substantial distance from the axis of the feed shaft and escapement wheel. In the form of my invention shown in the present instance there are three pivoted connecting links 60, connecting a substantially triangular bracket or member 62 operatively connected to the escapement wheel 30 with a similar bracket or member 64 operatively connected with the feed shaft 27.

The bracket 62 is fixedly secured to the lower side of the escapement wheel 30 by three headed screws 65 the stems of which pass through openings in the bracket and are threaded into tapped openings in the escapement wheel. The bracket 64 is retained against a flange of a hub 66 by a lower end portion of the hub passing through a central opening in the bracket 64 and having its lower end riveted to the bracket. The hub 66 is secured to the lower end of the feed shaft 27 by a set screw 70 threaded through the hub and bearing at its inner end against a flat portion of the shaft. This facilitates an assembly of the parts and provides for effecting a proper adjustment of the member 64 on the shaft 27.

One end of each of the links 60 is pivotally connected to the bracket 62 by a headed pivot pin 72 riveted to an associated lug 73 which extends downward from one corner of the bracket 62. The other end of each of the links 60 is pivotally connected to the bracket 64 by a headed pivot pin 74 riveted to an associated lug 75 which extends upward from one corner of the bracket 64. The lugs 73 and 75 on the brackets 62 and 64 respectively are so arranged that the links 60 are all equally spaced at equal and at considerable distances from the axis of the feed shaft and escapement wheel, the actual points of connection of the links being beyond the perimeter of the escapement wheel. Therefore, any slight wear that may take place at the pivots of the links 60 will hardly be appreciable in the creation of back lash between the escapement wheel and the shaft 27.

Referring to Fig. 1, it will be seen that the hub 66 is positioned longitudinally on the feed shaft 27 so that the end of each of the links 60 which is connected to the bracket 64 is lower than the end connected to the escapement wheel bracket 62. When the feed shaft 27 and bracket 64 are shifted upwardly by the shifting movement of the carriage from its lower case to its upper case position, the pivot 74 of each of the

links 60 is moved to a position which is substantially the same distance above the associated pivot 72; as it was below said pivot 72 before the shift took place, as will be seen from a comparison of the full and dotted line showing of the links 60 in Fig. 1. With this arrangement, the links 60 are shifted equal distances beyond a central horizontally disposed position, and accordingly the escapement wheel will have the same rotative position relative to the feed shaft 10 in either the upper or the lower case position. In other words, the links 60 are so arranged that no carriage movement in a letter space feed direction will be effected or permitted by a case shifting movement of the carriage and no relative rotative movement between the escapement wheel and shaft 27 can be effected in either the lower case or upper case position of the parts.

It will also be noted in Fig. 2 that there is a slight clearance between the sides of the links 60 and the heads of the pivots 72 and 74. This clearance will allow a slight twisting movement between the links and their pivots thus permitting a slight amount of lateral movement of the feed shaft 27 on its ball and socket support 28 at pivots 28a at the upper end of the shaft and relative to the escapement wheel 30. This feature of the present arrangement allows rotary motion to be freely transmitted from the feed shaft to the escapement wheel regardless of any change in axial alignment of the feed shaft which may be brought about by case shifting if the carriage shift member or rail 8 is not shifted exactly parallel with the axis of the feed shaft.

It will be seen that I have thus provided a simple and highly effective means for operatively connecting the feed pinion and the escapement wheel in a machine wherein the carriage in its entirety has a case shifting movement relative to the escapement wheel and the feed pinion is shifted with the carriage. In the specific form shown herein, the feed shaft is connected to the escapement wheel by pivoted links wherein the connecting pivot points are located outside the periphery of the escapement wheel. Thus, the extent of any lost motion that may occur at these pivots is not multiplied at the teeth of the escapement wheel and accordingly only a very slight extent of relative rotative motion can in any event be afforded between the teeth of the escapement wheel and the feed shaft.

In other words, I have provided a connecting means whereby the rotative back lash or lost motion between the escapement wheel and shaft that sometimes occurs in prior structures is substantially eliminated or reduced sufficiently to eliminate an improper carriage feed and also to eliminate or materially reduce any noise that may ordinarily occur in the operation of the escapement mechanism due to such back lash. It also will be clear that in my connecting means, any wear resulting from operation will be distributed, in the present instance over six points 60 at the pivots 72, 74, which together with the arrangement of the points of wear at a substantial distance from the axis of the feed shaft, reduce to a minimum any back lash that can take place in the connection and prevents any appreciable back lash from developing due to wear in the continued use of the machine.

Although I have shown and described the connecting means of my invention as located between the feed shaft and the escapement wheel, 75

obviously the connecting means may be located at any point between the case shiftable feed pinion 26 and the escapement wheel and the same results will be attained.

5. Various changes may be made in the construction, and certain features thereof may be omitted without departing from my invention as it is defined in the accompanying claims.

What I claim as new and desire to secure by 10 Letters Patent is:

1. The combination of a carriage mounted for case shifting movement, and escapement mechanism therefor including a feed shaft connected for rotative movement by letter spacing movements of said carriage and for axial movement by case shifting movements of said carriage, an escapement wheel mounted for rotative movement only, and means connecting said escapement wheel for rotation with said feed shaft but 15 affording axial movements of the feed shaft relative to the escapement wheel, said means including a plurality of connecting links extending transversely of said shaft and each pivotally connected to said feed shaft and to the escapement wheel to cause them to turn together and 20 also to afford an independent axial movement of the shaft, and operative substantially at equal distances each side of a transverse position in either case position of said feed shaft.

2. The combination of a carriage, a case shiftable member and escapement mechanism for the carriage including an escapement wheel and 25

a rotative feed device that turns as the carriage receives an intermittent letter space movement and has a relative axial movement during the case shifting movement of said case shiftable member, and connections substantially outside the periphery of said escapement wheel for connecting the escapement wheel and said rotative feed device to turn together but affording relative axial movements of the latter relatively to the escapement wheel, said connections including pivoted links arranged to operate substantially equal distances each side of a position aligning transversely of the axis of said rotative feed device during the case shifting movements thereof. 10

3. The combination of a carriage, a case shiftable member and escapement mechanism for the carriage including an escapement wheel and a rotative feed device that turns as the carriage receives an intermittent letter-space movement 20 and has a relative axial movement during the case shift movement of said shiftable member, and means connecting the escapement wheel and said rotative feed device to turn together but affording axial movements of the latter relative to the escapement wheel, said means including a connecting member arranged to operate during the case shifting movement substantially equal distances each side of a position extending at right angles to the axis of said 25 rotative feed device. 30

HENRY A. HEINRICH.
